UNITED STATES PATENT OFFICE.

WILLIAM C. WRIGHT, OF AMSTERDAM, NEW YORK.

DESIGN FOR A WHISK-BROOM HOLDER.

SPECIFICATION forming part of Design No. 17,836, dated October 25, 1887.

Application filed July 13, 1887. Serial No. 244,208. Term of patent 3½ years.

To all whom it may concern:

Be it known that I, WILLIAM C. WRIGHT, a citizen of the United States, residing at Amsterdam, in the county of Montgomery, State of New York, have invented a certain new and original Design for Whisk-Broom Holders, of which the following is a specification, reference being had therein to the accompanying drawing.

10 Referring to the drawing, which represents my design in perspective, A represents the broom-receiver, which in shape or configuration is like a canoe or boat. Between the ends A' thereof is the intermediate opening representing the usual hold, which in this instance passes through the bottom or keel and hull A. Through this opening the handle end of the whisk-broom B is passed. Suspension-rings

C are provided at one side of the canoe. A serpentine coil, A', is represented as a binding 20 on the canoe. An additional ornamental appearance is added by a paddle, D, having a bow-knot, D', on the side of the boat or canoe. This, however, is a minor detail.

What I claim is—

25 The design for a broom-holder, consisting of a canoe or boat shaped outline on each side of the holder, ornamented with a paddle or oar, substantially as shown and described.

In testimony whereof I affix my signature in 30 presence of two witnesses.

WILLIAM C. WRIGHT.

Witnesses:

ADAM REITZ,
JOHN WRIGHT.
